MASSAGE TABLE

Harley D. Niblack, Denver, Colo.

Application December 13, 1941, Serial No. 422,856

4 Claims. (Cl. 128—58)

This invention relates to a motorized massage table and has for its principal object the provision of a complete and highly efficient table device by means of which any desired portions of the human body can be efficiently massaged.

Other objects of the invention are to provide a massage table which can be regulated to concentrate the massaging action at any desired points on the body; which will, if desired, massage the feet simultaneously with the body; and which will enable the amplitude or intensity of the massaging action to be controlled by the operator.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a perspective view illustrating the improved massage table;

Fig. 2 is a longitudinal section therethrough;

Fig. 3 is a fragmentary end view thereof;

Fig. 4 is a cross section, taken on the line 4—4, Fig. 2;

Fig. 5 is a similar cross section, taken on the line 5—5, Fig. 2; and

Fig. 6 is a detail section through one of the massage rollers employed in the improved massage table.

The improved massage table comprises a table frame 10 supported on suitable legs 11 and provided with an open table top 31 surrounded by a protecting apron 43. Two horizontal, parallel shafts 12 are supported in suitable bearing brackets 13 from the table frame 10. Each of these shafts carries two flat belt pulleys 14 and two endless flat belts 15 extend between the respective pulleys of the adjacent shafts.

A plurality of parallel, roller shafts 16 extend between the two belts 15 and are secured at their extremities thereto. A cylindrical massage roller 17 is mounted on each shaft 16 intermediate the belts 15, preferably journaled on roller bearings 18 so that they will rotate freely with a minimum of friction.

The upper reaches of the two belts 15 ride on supporting tracks provided with track rollers 19. The tracks under each belt are separated at their middle portions to provide an open space, below

which, two pressure wheels 20 are carried. The pressure wheels are supported on the extremities of swinging levers 21 which are fixedly mounted on a cross shaft 22 supported from the frame 10. The cross shaft may be rotated by means of an adjusting lever 23. Thus, as the adjusting lever 23 is swung to the right, it will act to elevate the pressure wheels 20 causing the belts and their attached rollers to rise as they pass the middle of the table, as shown in broken line in Fig. 2.

The entire series of rollers 17 is covered by means of a top sheet 24 of canvas or rubberized fabric or other suitable flexible material. This top sheet is permanently attached adjacent the head extremity of the table, by means of an attachment strip 25, and is secured to and extends round a tension roller 26 adjacent the foot extremity thereof. The tension roller is provided with a suitable crank 27 by means of which it may be rotated to increase or decrease the tension in the sheet 24. A suitable ratchet wheel 28 and ratchet pawl 29 are provided to maintain the sheet 24 at any desired tension. A movable head rest 30 is supported over the sheet 24 at the head extremity of the table.

The belts 15 are driven by means of an electric motor 32 which, through the medium of a drive belt 33, rotates a countershaft 34 at reduced speed. Power is transmitted from the countershaft to one of the shafts 12 through the medium of a suitable V-belt 44. The direction of rotation is such that the massage rollers adjacent the table top move toward the foot thereof.

In use, a patient is placed upon the sheet 24, the latter being preferably covered by an individual, removable, sanitary sheet; the motor is started to cause the rollers at the top of the table to roll against the bottom of the sheet 24 under the weight of the patient's body so as to exert a massaging action on the contacting portions thereof. The amplitude or intensity of the massage can be controlled by the tension in the sheet 24. If this sheet is exceedingly tight, it will support the major portion of the weight of the body so that very light contact is made with the rollers, whereas if the sheet is exceedingly loose, the weight of the patient's body rests entirely on the massage rollers so that the latter exert a maximum massaging action thereon.

If it is desired to intensify the massaging action on the mid-portion of the patient, the lever 23 is moved to elevate the pressure wheels 20

to create a convex portion in the sheet 24 below the mid-portion of the patient.

The action of the massage rollers in traveling toward the foot of the table has a tendency to work the body of the patient toward the foot of the table. This is over-come by means of a foot rest 35 against which the patient may brace his feet to hold his body in place.

Means are also provided for massaging the feet if so desired. The latter consists of a pair of roller wheels 36 secured on a horizontal wheel shaft 37, which is supported above the table on suitable brackets 38 intermediate the foot rests 35. A plurality of freely rotatable foot rollers 39 extend between the peripheries of the two wheels 36. The wheels 36 and their rollers are contained within a suitable housing 40 at the foot of the table. The front of the housing is covered with a sheet 41 of flexible material which is stretched over and conceals the rollers 39. The patient may place his feet against this sheet 41 over the rollers 39 to obtain a foot message therefrom, or he may simply rest his feet against the foot rest 35 at each side of the rollers 39. The wheels 36 are driven from, and in an opposite direction to, the countershaft 34 by means of a crossed belt 42.

The adjusting lever 23 may be latched in any desired position by means of a locking sector 45 having latch openings 46 to be selectively engaged by a suitable latch (not shown) on the lever 23 as is usual in lever and locking sector constructions.

While a specific form of the improvement has been described and illustrated herein, it is desired to be understood that the same may be varied, within the scope of the appended claims without departing from the spirit of the invention.

Having thus described the invention, what is claimed and desired secured by Letters Patent is:

1. A massage table comprising: a tablelike frame; a pair of laterally extending, parallel, spaced-apart shafts supported adjacent the top of said frame; a pair of belt pulleys on each of said shafts; endless belts extending between the respective pulleys of the adjacent shafts; roller shafts secured at their extremities to the belts and extending in parallel relation therebetween; a freely rotatable roller mounted on each roller shaft; an idler wheel positioned beneath the

upper reach of each belt; levers supporting said wheels; manually operated means for swinging said levers to raise or lower said wheels for raising or lowering the middle portions of the upper reaches of said belts as desired; and means for driving said belts.

2. A massage table comprising: a tablelike frame; a pair of laterally extending, parallel, spaced-apart shafts supported adjacent the top of said frame; a pair of belt pulleys on each of said shafts; endless belts extending between the respective pulleys of the adjacent shafts; roller shafts secured at their extremities to the belts and extending in parallel relation therebetween; a freely rotatable roller mounted on each roller shaft; idler wheels positioned between the middle portions of the upper reaches of said belts; and levers supporting said wheels; a rotatable shaft to which said levers are secured; a hand lever secured to said last mentioned shaft for rotating the latter for raising and lowering said idler wheels to force said reaches upwardly and downwardly; and means for driving said belts.

3. In a massage table of the type having a plurality of parallel, horizontal rollers supported between a pair of traveling belts across the top of the table, means for adjustably supporting the mid-section of said belts comprising: a relatively large idler wheel beneath the mid-section of each belt; adjustable supporting means for said idler wheels; and a hand-operated lever for adjusting said supporting means to cause the latter to lift said belts upward at their wheel-engaging portions to cause said rollers to follow the natural arch of a patient's back.

4. In a massage table of the type having a plurality of parallel, horizontal rollers supported between a pair of traveling belts across the top of the table, means for adjustably supporting the mid-sections of said belts comprising: a relatively large idler wheel beneath the mid-section of each belt; levers supporting said idler wheels; a shaft, said levers being secured to and projecting from said shaft; means for locking said shaft at any desired position or rotation; and means for manually rotating said shaft to cause said levers to lift said wheels and said belts at their mid-sections so as to follow the natural curvature of a patient's back.

HARLEY D. NIBLACK.
